CAN CLOSING MACHINE

Albert Nickels, Baltimore, Md.

Application August 28, 1939, Serial No. 292,297

1 Claim. (Cl. 113—24)

This invention relates to a can closing machine, and has for its object to provide a machine adapted to close and seal a can by turning the flange of a removable ring under an annular flange on the can to hold the top on the can and hermetically seal it.

The invention consists of the novel construction and arrangement of the parts and combination of parts hereinafter more fully set forth in the following specification and pointed out in detail in the appended claim:

In the accompanying drawings—

Figure 1 is a front elevation of my invention, partly broken away, and showing a can in position to be sealed thereby.

Figure 2 is a top plan view of Figure 1.

Figure 3 is a front view of Figure 1.

Figure 4 is a detail inverted plan view of the holding head.

Figure 5 is a section of Figure 4 taken on the line 5—5 thereof.

Figure 6 is a detail end view of the slotted upright.

Referring to the accompanying drawings, forming part of this specification, and in which like reference numerals designate like parts throughout the several views thereof, 1 designates the base of the machine which is secured to a board 2 which latter may be held to a table or stand by clamps to hold the machine securely in position when being operated. The base 1 has a bearing 3 on one end thereof through which the upright 4 projects. The said upright 4 has a vertical slot 5 extending the entire length thereof into which the end of the screw 6 projects to hold the upright 4 in position and prevent it from turning in the bearing 3 as well as holding it securely in the adjusted position. Slidably mounted on the upright 4 is an arm 7 having a set-screw 8 which also projects into the vertical slot 5 of the upright 4 and permits the arm 7 to slide up and down on said upright 4 at the same time prevents the arm 7 from turning on the upright 4. The arm 7 rests on the upper end of the coiled spring 9 on the upright 4, the lower end of the coiled spring 9 rests on a collar 10 which is held in position by the pin 11. The upper end of the upright 4 is screw-threaded and has a hand wheel 12 screwed thereon and resting against the upper end of the arm 7. The said arm 7 can be forced down on the upright 4 by the hand wheel 12 being screwed in one direction and when screwed in the opposite direction the spring 9 will raise the said arm 7 on the

upright 4. In the outer end of the arm 7 is revolvably mounted a shaft 13 having a handle 14 on its upper end and an arm 15 on its lower end. Pivoted to the arm 15 at 16 is a lever 17 having a threaded boss 18 on one end in which the screw 19 operates, said screw 19 has a wheel 20 on one end and its inner end impinges against the lever 17. The end of the screw 19 is held against the lever 17 by the coiled spring 21, which latter has one end secured to the lever 17 and the other end secured to the arm 15. In the opposite end of the lever 17 is revolvably mounted a wheel 22 which rests against the flange 23 of a ring 24, the said ring 24 rests on the top of the can and 10 has the flange 23 projecting down in position to be forced under the flange of the can 25. The shaft 13 has a head 27 on its lower end which rests on the top of the can and holds it in position during the operation of sealing the can. 15 This head 27 does not revolve with the shaft 13 but is free thereon. As the handle 14 is turned the lever 17 is carried around the can 25 and the wheel 22 forces the flange 23 inwardly on each turn of the lever 17, each revolution of the lever 20 causes the projections of the wheel 20 to strike the projection 26 on the arm 7 turning the screw 19 which forces the opposite end of the lever 17, and consequently the wheel 22, inwardly against the flange 23 when the flange 23 is forced inwardly to seal the can, the wheel 12 is unscrewed allowing the arm 7 to be forced upwardly by the action of the spring 9 and the head 27 released from the can. The said head 27 is shaped on its lower surface to hold the sealing ring.

35 Having thus described my invention, what I claim is:

A can-closing machine comprising a base, an upright adjustable in said base, an arm adjustable on said upright, a projection on the lower surface of said arm, means for adjusting said arm on said upright, a shaft revolvably mounted in one end of said arm, means for revolving said shaft, an arm rigidly secured to the lower end of said shaft, a lever pivoted to said last-named arm, a roller mounted in one end of said lever, a screw adjustable in the opposite end of said lever and having its free end impinging against the arm on the lower end of said shaft, and a wheel on the opposite end of said screw having a plurality of projections each adapted to strike the projection on the lower surface of the first-named arm to turn said screw and force the roller in against the can being closed.

ALBERT NICKELS.
